ATTORNEYS.

UNITED STATES PATENT OFFICE.

ISAAC SCHNEER, OF NEW YORK, N. Y.

SHIRT.

SPECIFICATION forming part of Letters Patent No. 254,387, dated February 28, 1882.

Application filed December 31, 1881. (Model.)

To all whom it may concern:

Be it known that I, ISAAC SCHNEER, of the city, county, and State of New York, have invented a new and useful Improvement in Shirts, 5 of which the following is a full, clear, and exact description.

My invention consists in certain novel features applicable to dress-shirts and fancy shirts of flannel in part or as a whole, as hereinafter 10 described and claimed.

Reference is to be had to the accompanying drawings, forming part of this specification, in which similar letters of reference indicate corresponding parts in all the figures.

15 Figure 1 is a front elevation of a shirt of the improved construction. Fig. 2 is a front view of the neck portion with the collar turned inward. Fig. 3 is a similar view with the collar at the outside. Fig. 4 is a face view with the 20 front unlaced to show the construction. Fig. 5 is a section on line *x* *x*, and Fig. 6 a section on line *y* *y* of Fig. 4.

A is the shirt, of usual construction, except as hereinafter specified. *a a* are slits formed 25 in the lower part of the shirt-body, front and back, instead of in the sides, as usual. These slits extend from the bottom any desired distance upward, and by their position allow the shirt to open or give way sidewise or in the direction most natural and convenient. The 30 shirt may therefore be made longer and readily kept down to place, and there will be no danger of the shirt being torn by strain.

The shirt is also made with an open bosom, 35 formed to button by means of inner flaps, *b b*, attached at the inside, as shown in Figs. 4 and 6. The outer flaps, *c*, formed by the main body of the garment, are made with eyelets, through which a lacing-cord, *d*, is strung, 40 so that these outer flaps can be drawn up as closely as desired. This lacing is more reliable

and stronger than buttons, and gives an ornamental appearance to the bosom, as is desired on fancy flannel shirts.

The shirt is provided with a collar or neck-band, *g*, of ordinary character, and between the sides of the doubled strip forming the band (see Fig. 5) a collar, *e*, is attached, so that the collar, when turned inward, hangs straight below the band, and the band may be 50 used with a separate collar, as usual.

The collar *e* may also be turned outside, as shown in Figs. 1 and 3, for use in place of a separate collar. With dress-shirts this reversible collar avoids the necessity of changing 55 the garment when the collar is slightly soiled, because in that case the fixed collar can be turned in and another put on. With flannel shirts it gives the advantage of a collar of the same material, which, with a lawn-tennis shirt, 60 can be worn in the field and afterward readily replaced by another when the appearance of ordinary dress is desired.

I do not limit myself to the material of the shirt, as that may be varied according to its 65 intended use.

Having thus described my invention, what I claim as new, and desire to secure by Letters Patent, is—

1. The collar *e*, attached between the sides 70 of a doubled strip forming the band, to enable it to hang inwardly straight below the band or outwardly to serve the purpose of a separate collar, as shown and described.

2. In shirts having open bosoms, the combination of inner flaps, *b*, outer flaps, *c*, having eyelets, and lacing-cord *d*, substantially as 75 shown and described.

ISAAC SCHNEER.
